TAPE WRITER ATTACHMENT FOR TYPEWRITING MACHINES

Application filed December 22, 1930. Serial No. 504,173.

This invention relates to a tape writer attachment for a typewriting machine and it consists in the novel features hereinafter described and claimed.

An object of the invention is to provide an attachment of the character stated which may be readily applied to a typewriting machine by clamping the same upon the roller thereof and which is adapted to be actuated by the movement of a ribbon guide of the typewriter to move the tape longitudinally across the point of impact of the type. This is done by locking the carriage of the typewriter machine at any desired point so that the roller remains stationary as the keys are struck and the tape moving means is actuated so that the tape moves from right to left across the point of impact of the type and consequently the writing is produced upon the tape longitudinally thereof and may extend throughout the length of the tape.

The tape may have mucilage or glue applied to one side and addresses may be typed upon the tape and when the tape is removed from the machine the sections thereof bearing the addresses may be torn apart and applied to pieces of mail, as for instance, newspapers, magazines, pamphlets, circulars, tags, parcels, bundles, boxes and the like. The device may also be used to advantage for addressing letters, bills and literature at different times of the months by placing the addressed sections of tape upon envelopes. Thus considerable time is saved in view of the fact that in applying the addresses directly to the surfaces of an envelope it is necessary to move the carriage of the typewriting machine back and forth a number of times whereas the tape moves in one direction continuously across the point of impact of the type and no time is lost in returning the carriage or moving the same.

In the accompanying drawings:—

Figure 1 is a side elevational view of the tape writer attachment showing the same applied to the roller of a typewriting machine and with the ribbon guide at normal position.

Figure 2 is a similar view showing the ribbon guide elevated.

Figure 3 is a vertical transverse sectional view of the attachment cut on the line 3—3 of Figure 2.

Figure 4 is a similar view cut on the line 4—4 of Figure 2. 55

Figure 5 is a top plan view showing the attachment applied to the roller of a typewriter machine.

Figure 6 is a horizontal sectional view of the attachment cut on the line 6—6 of Figure 2. 60

As illustrated in the accompanying drawings, the tape writer attachment for a typewriting machine comprises clamp plates 1 and 2 which are hingedly connected together, as at 3. Said plates are provided with curved portions 4 which are adapted to grasp the upper portion of the roller 5 of the typewriting machine when the device is applied thereto and the nuts 6 upon the clamp bolts 7 are tightened. 65

The plate 2 is provided with spaced guides 8 and 8' and the stem 9 of an actuator 10 is slidable in said guides. The stem 9 is provided with a pin 11 and a spring 12 surrounds the said spring and bears at one end against the guide 8 and at its opposite end against the pin 11 and serves to normally hold the actuator 10 in a lowered position in the guides. The actuator is provided at its lower end with legs 13 which rest upon the upper end of the ribbon guide 14 of the typewriting machine. The actuator is provided at one side with an inclined arm 15 which bears against a roller 16 carried by a rod 17 which is slidable in guides 18 mounted upon the plate 2. A pin 19 passes through the rod 17 and a spring 20 bears at one end against the said pin and at its other end against one of the guides 18 and serves to hold the roller 16 against the edge of the inclined arm 15. The rod 17 is provided with a spring finger 21 which engages the teeth of a ratchet wheel 22 mounted upon the shaft 23 journaled in lugs 24 mounted upon the plate 2. A roller 25 is mounted upon the shaft 23 and is located opposite a roller 26 also journaled upon the plate 2. The tape 27 moves across the plate 2 and the point of impact of the type 80

28 is located opposite the roller 26. The tape 27 moves across the plate 2 and the point of impact of the type 85

28 is located opposite the roller 26. The tape 27 moves across the plate 2 and the point of impact of the type 90

28 is located opposite the roller 26. The tape 27 moves across the plate 2 and the point of impact of the type 95

28 is located opposite the roller 26. The tape 27 moves across the plate 2 and the point of impact of the type 100

of the typewriting machine and is trained between the rollers 25 and 26.

The operation of the device is as follows.

Assuming that the parts are in the positions as shown in Figure 1 of the drawings and a key of the typewriting machine is struck, the ribbon guide 14 moves from the lower position, as shown in Figure 1, to the elevated position, as shown in Figure 2, and at the same time the face of the type strikes the sur-

face of the tape 27 and a letter is imprinted upon the tape. As the ribbon guide 14 moves in an upward direction, the actuator 10 is lifted and the rod 17 moves longitudinally

in the guides 18 so that the end of the finger 21 moves past the pointed end of one of the teeth of the ratchet wheel 22. When the type key returns to its normal position, the ribbon guide 14 falls and the actuator 10 descends

under the pressure of the spring 12 and consequently the inclined arm 15 moves transversely across the end of the rod 17 and the said rod is moved against the tension of the spring 20 whereby the spring finger 21 comes

in contact with the edge of one of the teeth of the ratchet wheel 22 and the said wheel is partially turned whereby the tape is drawn across the point of impact of the face of the type and a new surface of the tape is brought to position for the next type which is struck.

Having described the invention what is claimed is:

1. A tape writer attachment for a typewriting machine having a vibrating ribbon guide and a roller, comprising a support adapted to be applied to the roller of the typewriting machine, a spring pressed actuator mounted upon the support and operatively engageable with the ribbon guide of the typewriting machine, said actuator having an outstanding inclined arm, a spring pressed rod slidably engaged by said arm, rollers journaled upon the support and adapted to receive a tape between them and means carried by one of the rollers for engagement with said rod.

2. A tape writer attachment for a typewriting machine having a vibrating ribbon guide and a roller, comprising clamp plates adapted to be applied to the roller of the typewriting machine, a spring pressed actuator mounted upon one of the plates and adapted to operatively engage the ribbon guide of the machine, said actuator having an inclined arm, a spring pressed rod mounted upon one of the plates and adapted to be moved by said arm, said rod having a spring finger, rollers journaled upon the plate and adapted to receive the tape between them and a ratchet wheel carried by one of the rollers adapted to be engaged by the spring finger of the rod.

3. A tape writer attachment for a typewriting machine having a vibrating ribbon guide and a roller, comprising a support, an

actuator slidable upon the support and adapted to operatively engage the ribbon guide of the typewriting machine, said actuator having an inclined arm, rollers journaled upon the support and adapted to receive the tape 70 between them, a ratchet wheel carried by one of the rollers, and a spring pressed rod adapted to be moved by the arm of the actuator and engageable with the teeth of the ratchet wheel.

4. A tape writer attachment for a typewriting machine having a vibrating ribbon guide and a roller, comprising a support, a spring pressed actuator mounted thereon and adapted to operatively engage the ribbon 80 guide, said actuator having an inclined arm, a spring pressed rod adapted to be moved by said arm and having a spring finger, rollers journaled upon the support and adapted to receive the tape between them, and a ratchet 85 wheel carried by one of the rollers and engageable with the spring finger of said rod.

5. A tape writer attachment for a typewriting machine having a vibrating ribbon guide and a roller, comprising a support, an 90 actuator slidably mounted upon the support and operatively engaging the ribbon guide and having an inclined arm, a spring pressed rod slidably upon the support and adapted to be moved by said arm, said rod having a spring finger, rollers journaled upon the support and adapted to receive the tape between them, and a ratchet wheel carried by one of the rollers and engageable with the spring finger of said rod.

In testimony whereof we affix our signatures.

JACKSON G. LANCASTER.
JOE K. DENTON.
